UNITED STATES PATENT OFFICE.

DAVID M. PIMES, OF BALTIMORE, MARYLAND.

DESIGN FOR A COMBINED FOLDING BED AND COUCH.

43,851.

Specification for Design.

Patented Apr. 15, 1913.

Application filed June 28, 1912. Serial No. 706,494. Term of patent 7 years.

To all whom it may concern:

Be it known that I, DAVID M. PIMES, a citizen of the United States, residing at Baltimore, in the State of Maryland, have invented a new, original, and ornamental Design for a Combined Folding Bed and Couch; and I do hereby declare the following to be a full, clear, and exact description of the invention, such as will enable others skilled in the art to which it appertains to make and use the same.

My invention relates to a design for furniture and more particularly for a combined couch and folding bed, or improved "Davenport" and the same will be found to be

fully illustrated in the accompanying drawings, in which the figure of the drawing shows a perspective view of my complete design.

I claim—

The ornamental design for a combined folding bed and couch, as shown and described.

In testimony whereof I have signed my name to this specification in the presence of two subscribing witnesses.

DAVID M. PIMES.
